SNOW PLOW HOUSING

Byron L. Ertsgaard, Riverside, Calif., and John A. Gale, Wayzata, Minn., assignors to Toro Manufacturing Corporation, Minneapolis, Minn., a corporation of Minnesota

Original design application Feb. 5, 1965, Ser. No. 83,697, now design Patent No. 205,531, dated Aug. 16, 1966. Divided and this application June 30, 1966, Ser. No. 2,869

Term of patent 14 years

(Cl. D35—2)

FIGURE 1 is a top plan view of a snow plow housing embodying our new design;

FIGURE 2 is a front perspective view thereof;

FIGURE 3 is a side elevational view thereof.

The undisclosed rear portion of the snow plow housing is substantially plain and follows the general configuration of the side panel members as best illustrated in FIGS. 2 and 3 on the drawing.

The dominant features of our design reside in the full line portions of the drawings.

The broken lines are shown for illustrative purposes only.

This is a division of Design application Ser. No. D.83,697, filed Feb. 5, 1965 and now Patent No. D.205,531.

We claim:

The ornamental design for a snow plow housing, substantially as shown and described.
